US00D637594S

(12) **United States Design Patent**
Carpenter, Jr. et al.

(10) **Patent No.:** **US D637,594 S**
(45) **Date of Patent:** **** May 10, 2011**

(54) **SMART FIXTURE**

(75) Inventors: **Robert Carpenter, Jr.**, Frisco, TX (US); **Thomas C. Feuerborn**, Flower Mound, TX (US); **Thomas N. Nealon**, Dallas, TX (US); **Rich Thompson**, Dallas, TX (US); **Brent McClintock**, Bedford, TX (US); **Jeff Wade**, Dallas, TX (US)

(73) Assignee: **J.C. Penney Corporation, Inc.**, Plano, TX (US)

(**) Term: **14 Years**

(21) Appl. No.: **29/359,811**

(22) Filed: **Apr. 15, 2010**

(51) **LOC (9) Cl.** **14-02**

(52) **U.S. Cl.** **D14/307**

(58) **Field of Classification Search** D14/302–307, D14/129, 900–902; D13/163; D18/4.1–4.6; D21/329, 332, 325, 369, 370; D99/28; 361/679.1, 361/679.02, 679.04, 679.21, 679.57, 724; 194/206; 235/379; 271/164; 705/43; D6/396, D6/697, 402; D20/10, 19; D24/200, 209, D24/185, 186

(57) **CLAIM**

The ornamental design for a smart fixture, as shown and described.

DESCRIPTION

This application is related to co-pending U.S. patent application Ser. No. 12/761,068, filed Apr. 15, 2010, entitled "Apparatus, Systems, and Methods for a Smart Fixture", the disclosure of which is incorporated by reference in its entirety.

FIG. 1 is a perspective view of the smart fixture showing our new design;

FIG. 2 is another perspective view of the smart fixture showing our new design;

FIG. 3 is a front elevational view thereof;

FIG. 4 is a side elevational view thereof;

FIG. 5 is a back elevational view thereof;

FIG. 6 is a top plan view thereof; and,

FIG. 7 is a bottom plan view thereof.

The broken lines in the drawings illustrated unclaimed portions of the smart fixture and form no part of the claimed design.

1 Claim, 5 Drawing Sheets
